**REFILL DEVICE FOR CARTRIDGES OF
 BALL POINT PENS**
 Harry H. Greis, 25 E. 213th St., Bronx, N.Y.
 Filed Nov. 20, 1959, Ser. No. 854,359
 2 Claims. (Cl. 141—30)

This invention concerns an ink filling device for ball point pens.

The filling and refilling of a ball point pen cartridge with the usual viscous ink employed for ball point pens presents a number of difficulties. The conventional ball point pen cartridge has a tube containing the viscous ink which is removed from the cartridge by the rolling ball tip. It is not possible to refill the cartridge from the tip end of the pen because the space between the rolling ball tip and its seat is too minute. Recourse must be had to the free open end of the ink containing tube of the cartridge.

It has been proposed in Patent 2,408,256 to provide a filling arrangement in which the cartridge tube has a flared open end and the portion of the tube adjacent the open end is threaded for insertion of the threaded end of a collapsible filling tube. This structure has been found disadvantageous since it requires special machining and processing to flare the ends of the cartridge tubes and to provide interior threads, all of which increases the cost of manufacture. Furthermore, there has been found the difficulty of releasing trapped air in the cartridge tube when a filling tube is screwed into the cartridge tube. A further disadvantage is that the above mentioned filling arrangement is not adaptable to use with conventional cartridge tubes having straight, unthreaded cylindrical ends. When the tip of the filling tube is inserted into the open end of a conventional cylindrical cartridge tube, air becomes trapped as the viscous ink passes from the collapsible tube. A further disadvantage is that the collapsible filling tube cannot be refilled with a fresh supply of ink.

The present invention is directed at overcoming difficulties and disadvantages heretofore encountered and at providing an improved filling device for a ball point pen cartridge.

According to the invention, there is provided a plastic container having a removable cap so that the container can be filled and refilled with a fresh supply of ink of desired viscous consistency. A long, cylindrical tube is secured in the other end of the container. This filling tube has a length at least as long as the interior of a cartridge tube of a ball point pen. The diameter of the filling tube is substantially equal to that of the interior of the cartridge and fits snugly therein in a good friction fit. The container is made of flexible plastic material so that it can be squeezed to reduce its volume and force ink therein into the filling tube, and from there to the cartridge tube. In another form of the invention, the filling tube is part of a plunger having a disk fitted in the cylindrical container of ink and adapted to be moved axially in the container for forcing the viscous ink out of the container through the filling tube.

The invention contemplates that the ink might also move out of the container into the filling tube and from the filling tube to the cartridge tube by gravity.

It is therefore a principal object of the invention to provide a novel ink filling device for a cartridge of a ball point pen.

It is a further object to provide an ink dispensing device adapted for filling cylindrical cartridge tubes of ball point pens.

Another object is to provide an ink dispensing device which serves effectively to remove air from a cartridge tube prior to filling and which prevents entry of air

2

into the cartridge tube during filling. It will, of course, be understood that if an air bubble is allowed to form in the body of ink in the cartridge tube of the ball point pen, then the pen will become inoperative. This is due to the fact that a ball point pen employs the phenomenon of capillarity to draw ink from the cartridge tube. If an air bubble reaches the tube, a void or space is created between the ball and the remainder of the body of ink. The occurrence of this void renders the pen inoperative.

10 For further comprehension of the invention, and of the objects and advantages thereof, reference will be had to the following description and accompanying drawings, and to the appended claims in which the various novel features of the invention are more particularly set forth.

15 In the accompanying drawings forming a material part of this disclosure:

FIG. 1 is an elevational view of a device embodying the invention.

FIG. 2 is a longitudinal sectional view of the device.

20 FIG. 3 is a perspective view on an enlarged scale of the filling tube per se of the device.

FIG. 4 is an exploded perspective view of the several components of the device, a portion of the filling tube being broken away.

25 FIG. 5 is a sectional view similar to FIG. 2 showing another form of the invention, part of the filling tube being shown in elevation.

FIG. 6 is a bottom plan view partially in section, taken on line 6—6 of FIG. 5.

30 FIG. 7 is a perspective view on a enlarged scale of the filling tube employed in the device of FIG. 3, part of the filling tube being broken away.

FIG. 8 is a side elevational view of the bottom end of the tube on an enlarged scale.

35 FIG. 9 is a vertical sectional view taken on line 9—9 of FIG. 8.

Referring to FIGS. 1, 2 and 4, there is shown a cylindrical container 10 having an open end formed with a bead 12 on which is detachably engageable a cap 14 having an inwardly turned annular lip 15 for engaging the bead 12. The container is made of flexible plastic material so that its cylindrical wall 11 can be squeezed as indicated by the dotted lines at 11' in FIG. 1 to reduce the internal volume of the container. The container may be filled with a supply of viscous ink 16. The bottom 18 of the container is formed with a central hole 20 through which extends a long cylindrical tube 22. The bottom end of the tube is cut away forming a slanting end edge 24 having a pointed extreme tip 24'. A passage 26 extends entirely through the tube, opening into the container 10. Secured to the inner end of the tube is a flange 28 best shown in FIGS. 2 and 3. This flange is embedded in a recess 30 in the inner side of the bottom 18 of the container. A removable conical cap 32 having a threaded bore 33 is provided for receiving and closing the tapered tip end 24 of the tube which is threaded at 25 near the tapered end. Tube 22 has an exterior length as long as or longer than the length of the tube 40 of the cartridge 42 shown in dotted lines 60 in FIG. 2. The diameter of the tube 22 is substantially equal to that of the interior of tube 40.

To fill the cartridge tube 40, the cap 32 is removed from tube 22. The container 10 is squeezed until the ink completely fills the tube 22 and appears at the tip end 24. The tube 22 is then inserted into the tube 40 as far as it will go while the walls of the container are still being squeezed. Any air which may be in the empty tube 40 will be discharged at the tip end 44 of the cartridge. The tapered tip 24 facilitates entry of tube 22 into tube 40. The air will flow out past the ball 45 in cartridge 42. After tube 22 is fully inserted in tube 40 there will be no air in either tube. The container

may then be squeezed further to force the ink out of tube 22 into tube 40. As the ink enters tube 40, the tube 22 is gradually withdrawn. This may occur due to the back pressure of ink entering tube 40 so that the tube 22 is forced out of tube 40 as it fills with ink. The minute space around the ball in its seat becomes closed because the air outside either forces the ball upward in its seat or the ink forces the ball down in its seat. Thus, the tube 40 is filled without the formation of air bubbles in the ink. After the tube 40 is filled, the wall 11 of the container is released and air-pressure pushes the ink remaining in tube 22 back into the container. The cap 32 may then be replaced. When all the ink in the container is discharged, the container can be refilled by removing cap 14.

In the form of the invention shown in FIGS. 5-7, a disk or plug 50 is provided. This disk has a recess 51 in which is secured flange 28 of the tube 22^a. This disk is made of leather, plastic or other suitable packing material which will engage the interior of wall 11^a of container 10^a with a snug friction fit. The bottom 18^a of the container is flat since the recess 30 of wall 18 is not required. Tube 22^a is longer than tube 22. The length of tube 22^a is substantially equal to the combined axial lengths of the interiors of container 10^a and of cartridge tube 40. Tube 22^a and disk 50 act as a plunger to apply pressure upwardly against the ink supply 16 in the container. The ink enters opening 23 in the disk and the aligned passage 26 in tube 22^a when the tube 22^a is pushed upwardly through hole 20 in the container toward cap 14^a. As the ink enters the tube 22^a the disk 50 moves upwardly in the container until finally the dotted line position 50' of the disk is reached near the top of the container. The top of the container can be externally threaded at 53 and cap 14^a can be correspondingly threaded to insure a secure removable engagement of the cap on the container. The container wall 11^a need not be flexible, and for this form of the invention is preferably rigid.

To fill the cartridge tube 40 when using the form of the invention shown in FIGS. 5-7, the cartridge 42 will be disposed upright with the ball 45 resting on a flat surface. The tube 22^a will first be forced upwardly so that its passage 26^a is filled with ink. Tube 22^a will then be inserted into tube 40 and air will be discharged past the ball 45 as previously described and tube 22^a will completely fill the interior of tube 40. The container 10^a will now be pulled downwardly axially. Tube 22^a will not be held and will be able to rise as the ink being discharged from its tip end 24 fills tube 40 and forces tube 22^a out of tube 40. Thus, as the tube 40 fills with ink the filling tube 22^a is automatically forced out by the ink. As a result no air bubbles can form in the tube 40. When the tube 40 is filled, cap 32 can be screwed on the tip end of tube 22^a. The tube 22^a can be left in its partially inserted position in container 10^a. If desired, the tube 22^a can be pulled out prior to putting on cap 32, which will cause air to enter the open tip end of the tube 22^a and force the ink therein back upwardly into the container. The cap 32 can then be screwed on the open end 24 of the tube 22^a.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A filling device for a cartridge tube of a ball point pen, comprising a cylindrical container of viscous ink,

said container having open and closed ends, a removable cap closing the open end of the container for repeatedly filling the container with said ink, a long cylindrical filling tube communicating with the interior of said container for receiving said ink therefrom, said tube having a length at least as long as that of said cartridge tube, and a diameter equal to the interior of said cartridge tube so that said cylindrical filling tube is forced out of said cartridge tube by pressure of ink as the cartridge tube is filled with ink from the filling tube, while air is prevented from entering the cartridge tube, said container having a rigid cylindrical wall, a cylindrical disk secured to said tube inside the container, said disk being slidable in said container in frictional contact with said cylindrical wall to apply pressure to the ink in the container, said disk having a central hole registering with a passage in said filling tube so that ink under pressure passes through said hole and passage, said closed end of the container being formed by a flat bottom wall with a central aperture, said filling tube being axially slidable through said central aperture as said disk moves in the container, said cap being threaded and engaged upon a corresponding threaded portion of said container to resist the pressure on the ink as said disk is moved in the container against the ink, said filling tube having a tapered tip end to facilitate entry of the filling tube in said cartridge tube, and another cap having a threaded bore for detachably engaging on a thread near the tip end of the filling tube, said filling tube having a length at least as long as the combined lengths of the interior of said container and said cartridge tube.

2. A filling device for a cartridge tube of a ball point pen, comprising a cylindrical container of viscous ink, said container having open and closed ends, a removable cap closing the open end of the container for repeatedly filling the container with said ink, a long cylindrical filling tube communicating with the interior of said container for receiving said ink therefrom, said tube having a length at least as long as that of said cartridge tube, and a diameter equal to the interior of said cartridge tube so that said cylindrical filling tube is forced out of said cartridge tube by pressure of ink as the cartridge tube is filled with ink from the filling tube, while air is prevented from entering the cartridge tube, said container having a rigid cylindrical wall, a cylindrical disk secured to said tube inside the container, said disk being slidable in said container in frictional contact with said cylindrical wall to apply pressure to the ink in the container, said disk having a central hole registering with a passage in said filling tube so that ink under pressure passes through said hole and passage, said closed end of the container being formed by a flat bottom wall with a central aperture, said filling tube being axially slidable through said central aperture as said disk moves in the container, said filling tube having a length at least as long as the combined lengths of the interior of said container and said cartridge tube so that one portion of the filling tube may enter said container while the remainder of the filling tube is disposed in the cartridge tube.
